UNITED STATES PATENT OFFICE.

SHERMAN HARROLD, OF HARTFORD CITY, INDIANA.

DESIGN FOR A WRIST MIRROR.

Application filed September 29, 1921. Serial No. 504,266. Term of patent 7 years.

To all whom it may concern:

Be it known that I, SHERMAN HARROLD, a citizen of the United States of America, residing at Hartford City, in the county of Blackford and State of Indiana, have invented a new, original, and ornamental Design for a Wrist Mirror, of which the following is a specification, reference being had to the accompanying drawing, forming part thereof.

In the drawing:

Fig. 2 is an edge elevation of the same.

I claim:

The ornamental design for a wrist mirror, as shown.

SHERMAN HARROLD. [L.s.]
